AUTOMATIC PICKUP DEVICE

Pete Blaire, Greenville, Pa.

Application February 3, 1947, Serial No. 726,144

3 Claims. (Cl. 294—67)

1

This invention relates to devices for automatically picking up various materials and more particularly to a device for picking up stacks of steel plates and the like.

The principal object of the invention is the provision of an automatic pickup device for handling various stacked materials.

A further object of the invention is the provision of a device having a plurality of material engaging members capable of automatic and simultaneous operation.

A still further object of the invention is the provision of an automatic pickup device having means facilitating its attachment to a crane.

A still further object of the invention is the provision of an automatic pickup device incorporating positive means for applying mechanical effort to portions of the device directly engaging material to be handled thereby.

The automatic pickup device shown and described herein has been designed to efficiently handle various stacked material such as steel plates as, for example, in a steel mill or fabricating plant. It is well known that in picking up stacked steel plates and the like it is common practice to pass a plurality of chains beneath the stack to form slings which are in turn attached to a hook carried by a crane. This operation necessitates manual guidance and placement of the chains and particularly the slings formed thereby during the actual pickup and carrying operation. As a consequence, considerable time is lost in handling stacked materials and frequently the men employed for handling the chains and the slings are injured by material shifting or slipping in the chain slings. These disadvantages of pickup and carrying operations of such materials are completely overcome by the present invention.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is a side elevation of the automatic pickup device.

Figure 2 is a top plan view taken on line 2—2 of Figure 1.

2

Figure 3 is an end elevation of the pickup device taken on line 3—3 of Figure 1.

Figure 4 is a cross section taken on line 4—4 of Figure 1.

By referring to the drawings and Figures 1, 2 and 3 in particular it will be seen that an automatic pickup device has been disclosed which comprises a main frame 10 having a secondary reinforcing and attachment frame 11 affixed thereto and preferably between spaced portions of the main frame 10. The secondary reinforcing and attachment frame 11 is provided with an opening 12 facilitating the attachment of a crane hook or the like thereto so that the main frame 10 may be picked up thereby. Depending from the main frame 10 and positioned at right angles thereto there are a plurality of depending sub-frame members 13 each of which is of semi-triangular shape, the apex portion of which is indicated by the numeral 14 and which is positioned between the spaced frame members 10 and affixed thereto. Positioned transversely of the several depending sub-frame members 13 there is a drive shaft 15 which extends axially with respect to the main frame 10 and is located therebeneath.

Means for imparting movement to the drive shaft 15 is provided and comprises a motor and gear reduction unit 16 which in turn is supported on a base 17 carried between a centrally located pair of the depending sub-frame members 13. Each of the sub-frame members 13 has a pair of arms 18 pivoted thereto by means of pivots 19. It will be observed by referring to Figure 3 of the drawings that each of the pairs of arms 18 pivoted to each of the sub-frame members 13 are in oppositely disposed relation to one another and are provided at their lowermost ends with inturned, pointed projections 20. The pointed projections 20 are adapted to underlie a stack of material to be picked up by the device.

It will also be seen by referring to Figure 3 of the drawings that each of the pairs of oppositely disposed arms 18 pivoted to each of the sub-frame members 13 are bent midway between their upper end lowermost ends so that in closed position the lower halves of the arms 18 lie on vertical planes spaced apart from one another thus enabling stacks of sheets or plates to be picked up between the arms when the pointed projections 20 are engaged therebeneath.

Means for imparting simultaneous and controlled movement to each of the opposed pairs of arms 18 pivoted to each of the sub-frame members 13 is provided and comprises a pair of shafts

21 and 22, respectively, positioned through each of the pairs of oppositely disposed arms 18, respectively. The shafts 21 and 22, respectively, unite the plurality of arms 18 and insure the transmission of any movement imparted to any of the pairs of arms 18 and to all of the others as well. Means for transmitting movement from the drive shaft 15 to the arms 18 is also provided and comprises crank members 23 and 24 positioned on the opposite ends of the drive shaft 15. Connecting rods 25 and 26 are adjustably affixed to the cranks 23 and 24 as by means of pivots 27 and 28. The lower ends of the connecting rods 25 and 26 are pivoted to meeting ends of oppositely disposed pairs of levers 29 by means of a longitudinally extending shaft 30. The shaft 30 engages each of the pairs of oppositely disposed levers as best shown in Figure 1 of the drawings. Each of the pairs of levers 29 are in turn pivoted at their outermost ends to the longitudinal shafts 21 and 22 heretofore described.

It will thus be seen that movement imparted to the drive shaft 15 will impart circular movement to the cranks 23 and 24 which movement will be imparted to the connecting rods 25 and 26 in the form of vertical movement. The vertical movement is in turn conveyed by the longitudinal extending shaft 30 and the pairs of levers 29 to the longitudinally extending shafts 21 and thence to the oppositely disposed pairs of arms 18.

By referring now to Figure 3 of the drawings it will be seen that solid lines thereon indicate the closed position of the arms 18 and dotted lines indicate the open position of the arms 18.

Still referring to Figure 3 of the drawings it will be seen that a guide member 31 is pivoted to each of the sub-frame members 13 forming the outermost ends of the automatic pickup device and slidably engage the connecting rods 25 and 26, respectively.

It will thus be seen that when the automatic pickup device is suspended from a crane, for example, it may be moved into position over a stack of steel plates to be lifted, the arms 18 caused to move apart by the energization of the motor and gear reduction unit 16 as heretofore explained and the device lowered over the stack of plates and the arms 18 caused to move together to bring the pointed projections 20 beneath the stack of plates to be lifted. When this is accomplished the crane may lift the automatic pickup device and the stack of plates therein and transfer it to any desired location where a stack of plates may again be set down by lowering the same to a position adjacent the supporting surface and energizing the motor and gear unit 16 to cause the arms to move apart.

It will be understood by those skilled in the art that blocks are usually provided underneath stacks of steel sheets or plates or the like to facilitate handling and that such blocks would receive the weight of the steel plates or sheets prior to the disengagement of the pointed projections 20 of the arms 18 of the automatic pickup device.

It will thus be seen that a simple and efficient automatic pickup device has been disclosed which will enable stacked flat materials, for example, to be readily handled without danger of slippage or injury to personnel. The device may be entirely operated by remote control. It will also be seen that the simultaneous and uniform action of the oppositely disposed pairs of arms 18 is insured by

the provision of the longitudinally extending and interconnected shafts 21, 22 and 30 and that any movement imparted to the said shafts is of necessity imparted to all of the arms 18 by the interconnection of these several parts. Due to the simplicity of formation of the automatic pickup device it may be readily disassembled for shipment and reassembled at the point of use and that in the case of breakage or damage of any of the component parts thereof they may be easily and simply replaced despite the interlocking assembled relation of the parts and their simultaneous movement in operation.

Having thus described my invention, what I claim is:

1. An automatic pickup device comprising a longitudinal frame member having a plurality of depending sub-frame members attached thereto and each of the said sub-frame members having a pair of oppositely disposed arms freely pivoted thereto, a longitudinally extending shaft positioned for engagement with each of the said oppositely disposed arms on one side of the said longitudinally extending frame said shaft engaging said arms inwardly from their outermost ends, and a secondary longitudinal shaft placed for engagement with each of the arms on the other side of the said frame, said shaft engaging said arms inwardly from their outermost ends 20 a third longitudinal shaft located midway between the first and second mentioned shafts, levers connecting the said shafts to one another and means for imparting vertical movement to the said centrally located shaft for moving the said oppositely disposed arms with respect to one another.

2. An automatic pickup device including a longitudinal frame member having a secondary reinforcing and pickup member attached thereto and extending thereabove, and a plurality of depending sub-frame members positioned at right angles to the said frame member, a longitudinally extending drive shaft journaled in each of the said sub-frame members, a plurality of longitudinally and horizontally spaced pairs of pivot members positioned on the said subframe members longitudinally thereof, a plurality of arms pivoted freely and one to each of the said spaced pivot members and depending therefrom, 40 a longitudinal shaft interconnecting the said arms pivoted to the pivots on one side of the said sub-frame members, said shaft engaging said arms inwardly from their outermost ends and a secondary longitudinal shaft interconnecting the 45 arms pivoted to the pivot members lying on the other side of the said sub-frame members, said secondary shaft engaging said arms inwardly from their outermost ends the said arms being arranged in oppositely disposed pairs and each 50 of the said arms having inturned lower end portions formed thereon, a third longitudinal shaft positioned midway between the said arms and levers connecting the shaft and second longitudinal shaft with the said third shaft and means 55 for imparting vertical movement to the said third shaft for simultaneously opening and closing the arms with respect to one another.

3. An automatic pickup device including a longitudinal frame member having a secondary reinforcing and pickup member attached thereto and extending thereabove, and a plurality of depending sub-frame members positioned at right angles to the said frame member, a drive shaft journaled in each the said sub-frame members 70 and extending longitudinally of the said device,

a plurality of pivot members positioned on the said sub-frame members on a horizontal plane and spaced transversely and longitudinally with respect to one another, a plurality of arms pivoted one to each of the said spaced pivot members and depending therefrom, a longitudinally extending shaft interconnecting the said arms pivoted to the pivots on one side of the said sub-frame members, said shaft engaging said arms inwardly from their outermost ends and a secondary longitudinally extending shaft interconnecting the arms pivoted to the pivot members lying on the other side of the said sub-frame members, said secondary shaft engaging said arms inwardly from their outermost ends the said arms being arranged in oppositely disposed pairs and each of the said arms having inturned lower end portions formed thereon, a third longitudinal shaft positioned midway between the said arms and links connecting the first and second mentioned longitudinally extending shaft with the said third shafts and means for imparting vertical movement to the said third shaft for simultaneously opening and closing the arms with respect to one another, the said means for im-

parting vertical movement to the third shaft comprising said drive shaft, a motor and gear reduction unit connected to the said drive shaft, cranks positioned on the said drive shaft and connecting rods connecting the said cranks with the said third shaft.

PETE BLAIRE.
